UNITED STATES PATENT OFFICE.

ERNEST DU PONT, OF WILMINGTON, DELAWARE, ASSIGNOR TO BALL GRAIN EXPLOSIVES COMPANY, OF WILMINGTON, DELAWARE, A CORPORATION OF DELAWARE.

PROCESS OF MANUFACTURING PELLETS OF EXPLOSIVE MATERIAL.

1,295,975.

Specification of Letters Patent.

Patented Mar. 4, 1919.

Application filed May 1, 1917, Serial No. 165,671. Renewed January 16, 1918. Serial No. 212,159.

To all whom it may concern:

Be it known that I, ERNEST DU PONT, a citizen of the United States, residing at Wilmington, county of New Castle, and 5 State of Delaware, have invented a new and useful Improvement in Processes of Manufacturing Pellets of Explosive Material, of which the following is a full, clear, and exact description, reference being had to the 10 accompanying drawings, which form a part of this specification.

The object of the invention is the manufacture of pellets of explosive material for use in the central tubes of shrapnel shells, 15 although the invention is not limited to this special purpose. These pellets are made in cylindrical shape and are provided with axial orifices, and are each of a size adapted to fit the central tube of a shell. The pellets are assembled in the tubes one behind the other and act as a fuse to connect the 20 firing means at the point of the shell with the mass of explosive material at its rear.

Difficulty is encountered in making these 25 pellets so that they will resist the strains, incident to the discharge of a shell, tending to more or less crush the pellets and thus obstruct the central hole formed by the axial orifices of the string of pellets, thereby preventing the proper burning of the fuse.

The more particular object of the invention is to so manufacture the cakes or pellets that the final product will be one in which the particles of the cake will more strongly 30 adhere and effectively resist crushing strains.

The carrying out of the process is not dependent upon the use of any particular apparatus, but in order to enable those skilled in the art to carry out the process 40 without the necessity of experiment, the mechanical instrumentalities that it is preferred to employ will be particularly described and shown. Some of these instrumentalities are separately old, while others 45 exhibit features of independent novelty.

The first step in the process is to take a quantity of grained, unglazed, explosive black powder and place it in an open-topped bowl, turning on an axis inclined to the 50 horizontal. While the bowl is rotating, water is sprayed into its open top, preferably from an atomizer connected with a small vessel of water and with air under

pressure. Thereby the water is distributed uniformly throughout the mass of powder. 55 It is found that it is quite important to carefully predetermine the percentage of water added, which should be between 1.9 and 2.1 per cent. of the powder, although a somewhat larger or smaller proportion of water 60 than the range specified will give satisfactory, if inferior, results. The function of the water is to dissolve a proportion of the saltpeter of the powder and to enable the particles of powder, when subsequently 65 molded under pressure, to stick together. The proportion of water specified is sufficiently high to attain this result but is not in excess of that required to fill the interstices or voids in the finished cake. 70

The moistened powder is then transferred to a mill in which it is ground with gasoline so as to obtain a mass containing grains of different sizes; or perhaps, more accurately, a mixture of grains and dust: the finer particles filling more or less completely the interstices between the larger grains. The mill preferably comprises a cylinder, revolving on a horizontal axis containing two heavy cylindrical rollers. The quantity of 80 gasoline employed should be sufficient to cover the mass and render it fluid during the process of grinding. As an example, with the grinding operation conducted at a temperature at 20° C., approximately equal 85 parts by weight of powder and gasoline have been found satisfactory.

After the grinding operation, the mixture may be conveyed to a vessel containing a 90 rotary stirrer, which is continuously operated to prevent settling and maintain the powder in suspension in the gasoline. Thence the mixture is conveyed into a main supply pipe, from which branch other pipes, controlled by valves, leading to individual 95 molds. A number of these pipes may be operated in unison so as to simultaneously fill a series of molds.

The molds are of cylindrical shape and a fixed pin extends through the axis of each mold, this pin forming the central hole in the finished cake or pellet. The bottom of the mold is a movable plunger which, when depressed to allow the inflow of the mixed 100 gasoline and powder, forms a mold of much 105 greater height than the length of the fin-

ished pellet. The mold, after it is entirely filled with the mixture, closed at the top by a shutter, and by hydraulic power the plunger is moved up while the shutter is pressed down. The gasolene, or the larger part thereof, is forced out between the inner wall of the mold and the plunger and the powder is compacted into a mass of the desired density. The flow of water to each 10 hydraulic cylinder actuating the corresponding mold plunger is controlled by a check valve, so as to effect a slow movement of the plunger on its compression stroke, thus giving ample time for the escape of 15 the gasolene and avoiding the possibility of explosion, and also allowing a quick return of the plunger. Before the ejection of the pellet from the mold, the same is held under pressure for a time to produce the desired degree of hardness in the pellet. The shutter is then removed and the plunger raised to eject the pellet, which may be guided by a chute to a conveyer.

The molds act as measures which, owing 25 to the fact that the powder is maintained evenly suspended in the gasolene, predetermine the quantity of powder in each pellet.

By means of the conveyer, the pellets are carried through a dry-house, which is heated 30 to a temperature of, preferably, about 100 degrees centigrade and properly ventilated.

While I have specified and claimed the grinding of the moistened granular powder 35 in gasolene, it will be understood that I intend to comprehend the use of any liquid which, for the purposes of my process, is an equivalent. Any liquid which has little or no solvent or chemical action upon the powder ingredients and which will not render the grinding operation unsafe and which is not miscible with water and does not disturb the fixed relationship of the powder to the moisture may be substituted.

40 The apparatus hereinbefore described in general terms is shown in the drawings, in which—

Figure 1 is a sectional view illustrating the apparatus for carrying on the first step 45 in the process, that is moistening the explosive.

Fig. 2 is a similar view illustrating the grinding apparatus.

Fig. 3 is a front view, partly in section, 50 of the machine for compressing the explosive mixture into pellets, together with the hydraulic connections and operating valves.

Fig. 4 is a side view of one of the compressing machines, principally in central section, together with the arrangement for feeding the mixture and carrying off the pellets.

Fig. 5 is a detail sectional view of one of the compressing plungers.

55 Fig. 6 is a diagrammatic plan view of a

gang of compressing machines with the hydraulic connections and the feed lines from the stirring tank.

Fig. 7 shows the stirring tank in vertical section.

Fig. 8 is a perspective view of a portion of the dry-house.

Fig. 9 shows one of the finished pellets.

The device for moistening the explosive 75 thoroughly comprises an open bowl *a* carried on a shaft *b* mounted in bearings at an angle of approximately 45° to the horizontal. Shaft *b* is shown as rotated by bevel gears *c* from a horizontal shaft *d*. A small vessel *e*, for the water, is mounted on some 80 stationary support *f* adjacent to the opening in bowl *a*. Vessel *e* is provided with an air pressure pipe *g* and an atomizing nozzle *h* for spraying the water into the opening in the bowl.

The thoroughly moistened explosive is then placed in the barrel *i* together with gasolene. Barrel *i* is caused to rotate upon rollers *j*, and carries within it two cylindrical rolls *k*, which by their own weight crush 90 the powder grains when the barrel is rotated. This apparatus is similar to that used in an invention filed by me in the Patent Office December 13, 1913, whereby powder grains are crushed to a powder.

95 In the present invention, this step in the process is carried on only to a limited extent until sufficient of the powder grains have been pulverized to fill in the interstices between the remaining uncrushed grains.

The mixture of gasolene and crushed and uncrushed powder grains is then transferred to a stirring tank *l* shown in Figs. 6 and 100 7. The contents of this tank are kept agitated by means of a beater *m* rotated by gearing indicated at *n*, thus keeping the powder in a state of suspension in the gasolene.

105 A feed main *o* leads from the bottom of tank *l* to a line running in proximity to a gang of presses, and thence back to tank *l*, discharging the overflow into said tank. A pump *p* in feed main *o* keeps up this circulation.

110 A short passage *q* leads from main *o* to the mold *r* of each press, and a valve *s* which controls the flow through each passage *q* is normally held closed by a spring *t* and is opened by means of a lever *u*. Lever *u* for feeding the mold of each press is actuated 115 by a cam *v* mounted on a common shaft *w*. Thus by turning the shaft *w*, all the molds may be fed and the quantity fed to each determined.

120 The seat for valve *s* is placed directly at the junction of passage *q* with feed main *o*, thus leaving no dead space behind the valve wherein the mixture might settle and prevent its opening.

125 The casting forming the housing *x* for

valve s is of special construction to prevent leakage and yet allow free movement of the valve stem y . This stem passes out through an opening in housing x without any stuffing box, the mixture being prevented from exuding around the stem, by an internal depending flange z , through which valve stem y also passes. The flow of the mixture is all outward through the open passage q . Where it strikes flange z it is deflected downward, and any of the mixture that might pass through the flange with the valve stem will be stopped by the end wall of the housing and fall again into passage q .

15 Each press comprises a fixed vertical mold 10, the top of which is closed by a sliding shutter 11, and the bottom of which is formed by the plunger 12.

Plunger 12 is actuated as follows: Above 20 and in line with mold 10 is a hydraulic cylinder 13 with a piston 14 whose rod 15 passes through the upper end of the cylinder and through a fixed bearing guide 16. Above the cylinder, rod 15 carries a yoke frame 17, the 25 side rods 18 of which pass downward through bearings on either side of mold 10, and which on its lower cross piece carries the centrally located plunger 12 in sliding relation with mold 10. Cylinder 13 is carried 30 on a post 19 which has a slight vertical movement in a bearing 20 fixed to the frame of the machine. Below this bearing, post 19 has an extension 21 which reaches down to shutter 11. Extension 21 is bifurcated and 35 its two feet are grooved as at 22, the sides of the grooves forming a guide-way for the shutter 11, and the tops of the grooves abutting upon the top of the shutter when post 19 is pressed downward in its bearing 20.

40 By this arrangement, it will be seen that when piston 14 is pressed upward, yoke 17 will be forced up and with it plunger 12, compressing the contents of the mold 10 against shutter 11. At the same time, cylinder 13 will be pressed downward until extension 21 abuts upon shutter 11 and holds 45 it down over the top of the mold. Thus, no matter what pressure is used to compress the mixture in the mold by forcing up plunger 12, exactly the same pressure is acting to 50 keep the top of the mold closed against it.

The bifurcation of extension 21 allows the end of passage q to enter and deliver the mixture directly into the top of the mold 55 when the shutter 11 is open. Shutter 11 is slidably actuated to open or close the top of the mold by means of a bell crank 23; a pin 24 in one arm of said bell crank loosely engages in a hole in the shutter, and a hole in 60 the other arm of said bell crank loosely engages a pin 25 attached to a slideable rod 26.

It will be understood there is a bell crank 23 for each press, and that rod 26 extends 65 along in front of the gang of presses, and is longitudinally movable to open or shut the

shutters on all the presses in the gang at once.

Plunger 12 is hollow and a fixed rod 27, supported by a bracket 28, below yoke 17, passes up through said yoke, through the 70 plunger and through the mold to the top thereof. This rod 27 forms the longitudinal hole in the pressed pellets. Plunger 12 is cut away, exteriorly and interiorly for most of its length, but at the top for a short distance at 29 it fits the mold fairly, and also the central rod 27, so that none of the powder in the mixture may pass in the pressing operation, but allowing the fluids to slip by. The fluid thus expressed, and any that may 80 leak out from beneath the shutter 11, is collected in suitable cans 30 and may be used over again in the grinding process.

The cylinders of the presses receive hydraulic pressure through mains 31, 32, 85 which are controlled by 4-way valve 33. As shown in Fig. 3, hydraulic pressure is admitted through pipe 34 from a source not shown, passes through valve 33 into main 31, whence it is led by short connection 36 90 to the bottom of each cylinder 13. As the piston is thus forced up, the fluid above it escapes by way of connection 37 to main 32, and thence through valve 33 to exhaust pipe 35. In order to prevent too quick action of 95 the piston and plunger 12, in its compressing stroke, a check valve 38 is interposed in the connection 37 to each cylinder 13. This valve is slightly cut away as at 39, which allows the fluid to pass out as described above, but throttles it somewhat, so that although piston 14 will be pressed up with the full hydraulic pressure its motion will be relatively slow.

When the pressure has been on sufficiently 105 to form the pellet in the mold, valve 33 is turned 90° until its handle 40 reaches the broken line position in the figure. This reverses the hydraulic flow, and as check valve 38 opens freely in this direction, piston 110 14 and plunger 12 descend rapidly.

According to the plan illustrated in Fig. 6, the presses are arranged in two gangs, each gang being operated by a 4-way valve 33, the two valves being placed near each other. In this way an operator may stand midway in the line of presses and operate one of said valves to make one-half the presses active while the other valve is turned so that the other half of the presses are discharging. He may then turn both valves and reverse the operation in both of the sets of presses. In this way he is enabled to use only one-half the hydraulic power and to use it practically continuously, instead of 120 the full power for all the presses used only half the time.

After the pressing operation is completed, valve 33 is turned sufficiently to relieve the pressure of extension 21 upon shutter 11, and 125

rod 26 is operated to open all the shutters. Pressure is then again applied and plunger 12 is raised to the top of the mold ejecting the pellet. Then the 4-way valve is reversed 5 to the exhaust position as described above. First, however, rod 26 may be again operated, closing shutters 11, which push the ejected pellets into chutes 41 leading through the backs of the presses into a conveyor 42, 10 running in a trough 43.

During the lowering movement of plungers 12, shaft *w* is operated to open valves *s* and mixture is fed through passage *q* and delivered into the mouth of the mold. The 15 drawing down of plunger 12 aids in this filling of the mold by sucking the mixture in after it.

The finished pellets, see Fig. 9, are carried by the conveyor 42 to a dry-house 44, shown 20 in Fig. 8. The dry-house is not wide, very low, but of extreme length, and is provided with heating pipes 45, and with side rollers 46, upon which trays 47 of pellets may be slid in, and one behind another push each 25 other through the dry-house. The ends remain open, and the progress of the pans of pellets through the dry-house is so slow as to thoroughly and completely remove all moisture from the pellets. Moreover, this 30 is accomplished with a minimum of risk of explosion, as the heat given off by pipes 45 need not be excessive, and also the powder pellets being strung along in the comparatively small trays 47, present no great 35 amount of the explosive at any one place.

Having now fully described my invention, what I desire to claim and protect by Letters Patent is:

1. The process of making explosive material, which consists in moistening unglazed explosive black powder, grinding the same to obtain a mixture of grain and dust, and then molding the same.

2. The process of making pellets of explosive material, which consists in moistening unglazed explosive black powder, grinding the same to obtain a mass of different sized grains, and molding the same under pressure.

3. The process of making pellets of explosive material, which consists in moistening grained unglazed explosive powder, grinding the same in gasoline, and molding the explosive into pellets.

4. The process which comprises evenly moistening grained unglazed explosive black powder with approximately two per cent. of water and subsequently forming the explosives into pellets, the moistening operation dissolving a proportion of the salt-peter and causing the particles of the pellets to adhere together and resist crushing strains.

5. The process of making pellets of explosive material, which consists in moisten-

ing grained unglazed black explosive powder with approximately two per cent. of water, grinding the moistened powder in gasoline to obtain a mass of different sized grains, and molding the explosive into 70 pellets.

6. The process of making pellets of explosive material, which consists in agitating a mass of grained unglazed black powder and simultaneously spraying the same with 75 water in a finely divided state to effect a uniform moistening of the mass, grinding the moistened powder, and molding the explosive into pellets.

7. The process of making pellets of explosive material, which consists in subjecting a mass of grained unglazed black powder to a rotary tumbling action and simultaneously spraying the same with water in a finely divided state, grinding the moistened powder, and molding the explosive 85 into pellets.

8. The process of making pellets of explosive material, which consists in moistening grained unglazed black explosive powder, 90 grinding the moistened powder in a quantity of gasoline sufficient to render it fluid, flowing the mixture into molds, and subjecting it to pressure to expel a substantial part of the gasoline and mold the pellets. 95

9. The process of making pellets of explosive material, which consists in moistening grained unglazed black explosive powder, grinding the same in gasoline, flowing the gasoline and powder into a mold, subjecting the same to pressure while expelling a substantial portion of the gasoline, and maintaining the pressure to produce the desired degree of hardness of the pellets.

10. The process of making pellets of explosive material, which consists in uniformly moistening a mass of grained unglazed explosive black powder, grinding the same in gasoline to obtain a mass of different sized grains, molding the explosive under pressure while expelling a substantial part of the gasoline, and drying the molded pellets.

11. The process of making pellets of explosive material, which consists in moistening grained unglazed explosive powder, 115 grinding the same in gasoline, molding the explosive into pellets, and subjecting the pellets to a temperature of approximately 100 degrees centigrade.

12. The process of making pellets of explosive material, which consists in moistening grained unglazed black explosive powder, grinding the same in gasoline, transferring the mixture of gasoline and powder to a mold and regulating the proportions 125 therein of gasoline and powder to predetermine the size and weight of the finished pellet, and molding the explosive into pellets.

13. The process of making pellets of explosive material, which consists in moisten-

ing a mass of grained unglazed explosive black powder, grinding the same in gasoline to obtain a mass of different sized grains, the quantity of gasoline being sufficient to render the mixture fluid, agitating the mixture after grinding to prevent settlement, flowing the mixture into molds, subjecting the mixture to pressure to expel

a substantial part of the gasoline and mold the powder into pellets, and drying the 10 molded pellets.

In testimony of which invention, I have hereunto set my hand, at Wilmington, Del., on this 28th day of April, 1917.

ERNEST DU PONT.
